UNITED STATES PATENT OFFICE.

JAY M. JOHNSON AND HUGO J. BAUR, OF CHICAGO, ILLINOIS; SAID BAUR ASSIGNOR TO
SAID JOHNSON.

FARE-REGISTER.

1,159,771.

Specification of Letters Patent.

Patented Nov. 9, 1915.

Application filed March 2, 1910. Serial No. 546,801.

To all whom it may concern:

Be it known that we, JAY M. JOHNSON and HUGO J. BAUR, citizens of the United States, and residents of the city of Chicago, 5 in the county of Cook and State of Illinois, have invented certain new and useful Improvements in Fare-Registers; and we do hereby declare that the following is a full, clear, and exact description of the same, 10 reference being had to the accompanying drawings, and to the numbers of reference marked thereon, which form a part of this specification.

This invention relates to that class of fare 15 registers set forth in the prior application for patent of Jay M. Johnson for "cash registering and counting mechanisms for street cars and other purposes," filed April 5, 1909, Serial No. 487,970, in which the fares as deposited are counted and registered and the 20 coins of different denominations are separated each into an individual compartment, as set forth in the application for United States Letters Patent of Jay M. Johnson for 25 "coin counting and registering mechanisms," filed June 26, 1909, Serial No. 504,510.

The object of this invention is to afford a 30 fare register of the class described in which the registering of the coin is effected automatically and mechanically and to afford a construction in which opportunity for error is reduced to a minimum.

It is also an object of the invention to afford a construction in which each coin 35 when passed into the machine serves to actuate a gear for a predetermined distance dependent upon the size of the coin, the movement of said gear by the coin being communicated to a mechanical register for the 40 coin.

It is also an object of the invention to afford a construction in which the coins when delivered into the coin box are safely retained therein beyond a possibility of removal by dishonest employees or others and 45 also to afford a construction in which resistance due to friction is reduced to a minimum and in which the highest possible speed and accuracy of operation is assured with minimum expenditure of power.

The invention embraces many novel features and consists in the matters hereinafter described and more fully pointed out and defined in the appended claims.

In the drawings: Figure 1 is a transverse 55 section taken through the casing, showing parts of the machine in elevation. Fig. 2 is an enlarged section on line 2—2 of Fig. 1. Fig. 3 is a face view of the carrying wheel with the mechanism above the same removed. 60 Fig. 4 is a view in rear elevation of the mechanism removed from the case. Fig. 5 is an enlarged fragmentary view in elevation of a part of the trip mechanism for the fare box. Fig. 6 is a section on line 6—6 of Fig. 65 4, with parts omitted. Fig. 7 is a section on line 7—7 of Fig. 4, with parts omitted. Fig. 8 is a section on line 8—8 of Fig. 6, with the frame plate omitted. Fig. 9 is a section on line 9—9 of Fig. 6, with parts 70 omitted. Fig. 10 is a section on line 10—10 of Fig. 5. Fig. 11 is a section on line 11—11 of Fig. 4, with the center shaft and actuating mechanism in elevation. Fig. 12 is a section on line 12—12 of Fig. 13. Fig. 13 is an 75 enlarged section on line 13—13 of Fig. 12. Fig. 14 is an enlarged sectional detail of a part of the fare box. Fig. 15 is a section taken on line 15—15 of Fig. 2, with parts omitted. Figs. 16 and 17 are detailed views 80 illustrating the construction of the coin chute in the fare box. Fig. 18 is a face view of the coin chutes leading from the counting stations to the respective coin receptacle showing the same removed from the machine. 85

As shown in the drawings: 1, indicates frame members, as shown, constructed in the form of right angled triangles and having the face or bearing surface thereof inclined at a sufficiently steep angle of inclination for the purposes of the machine. Secured on the inclined faces of said frame members is a frame plate 2, on which the counting and registering mechanism is supported. Said frame plate 2, as shown, is 90 countersunk upon its face to afford a recess of uniform depth in which is rotatably supported the coin carrying wheel whereby the coin are carried to counting position. Said carrying wheel is journaled on said frame 95 plate 2, by means of a shaft 4, journaled in a central rearwardly and downwardly directed hub 5, and comprises a circular disk 6, integral with or otherwise rigidly secured on shaft 4, to which is secured a rim 7, by 100 means of screws or otherwise. Said rim comprises a relatively thin plate of metal conveniently steel, having pockets arranged 105

in its periphery equal distances apart. As shown, each of said pockets is adapted to carry more than one size of coin. For this purpose, the bottom of the pocket is cut on 5 an arc of a smaller radius than the outer portion of the pocket, thus permitting a large coin to be held considerably extended from the pocket and permitting a smaller coin to fall farther into the pocket and to 10 project but a slight distance beyond the same at its edge. Keyed on said shaft 4, at the rear side of the frame plate is a worm gear 8, which meshes with a worm 9, secured upon a shaft 10. Said shaft is the driving 15 shaft of the machine and may be operated either manually or by means of a suitable motor, as desired, and by its rotation acts to continuously rotate the carrying wheel.

Adjustably secured by threading or otherwise upon the externally threaded hub or boss 5, of the frame plate 2, is an anti-friction or ball bearing 11, on which is secured to rotate freely therewith, a spur gear 12, and a ratchet wheel 13, and mounted upon 25 the frame plate at any convenient point is a spring pressed detent 14, (see Fig. 4) the head of which at all times engages the ratchet wheel 13, above mentioned to hold said gear and ratchet from throwing inaccurately because of the momentum of the 30 moving parts.

Journalized on the frame plate is an accumulating shaft 15, which is provided with a bevel gear 90, meshing with a bevel gear 35 91, on a shaft 92, and a gear 16, is provided on said shaft 92, which meshes with gear 12, as shown in Figs. 2 and 4. Said shaft 15, is provided at its outer end with a bevel pinion 17, which meshes with a cor- 40 responding bevel pinion 18, which drives the veeder or other suitable recorder 19, secured at the top of the frame plate.

As shown, the machine is designed to register pennies, nickels, and dimes, and for this 45 purpose, as shown, counting stations are provided around the periphery of the carrying wheel, indicated by 20, 21 and 22 respectively, being appropriated to nickels, pennies and dimes respectively.

50 Referring first to the mechanism for recording nickel or five cent pieces: 23, indicates a frame or bar rigidly secured on the frame plate and extending upwardly. Journalized in the lower part of said bar or frame 55 and closely adjacent the frame plate is a shaft 24, provided at its outer end with a star wheel 25, having five hooked teeth 26, thereon, which project through a slot in the frame plate beyond the periphery of the 60 carrying wheel. At its opposite or inner end said shaft is provided with a bevel pinion 27, which meshes with a corresponding bevel pinion 28, driving a shaft 29, on which 65 is a mutilated gear 30, as shown, provided with five teeth arranged at equal distances

apart and projecting into position to mesh with a pinion 31, journalized on said beam or bar 23. Said pinion 31, meshes with the master gear wheel 12, so that as said mutilated gear is revolved the pinion 31, is intermittently rotated in turn characteristically rotating the master 12, and thence the accumulating shaft 15, and veeder 19. Set in advance of said star wheel 25, is a guide plate 32, bolted on the main frame plate and projecting over the channel or passage for the coin and to the periphery of the carrying wheel and serving to hold the coin down after the periphery thereof engages the star wheel and in the construction shown the machine being designated to count nickel fares, each nickel passing beneath the guide 32, and engaging the star wheel 25, of necessity rotates the shaft 24, one fifth of a revolution. In consequence, the mutilated gear 30, is provided with five teeth spaced equal distances apart, each of which serves to rotate the pinion, master gear and accumulator shaft sufficiently to mark up one fare on the veeder.

90 A brake is provided on the counting shaft to obviate any inaccuracy on account of momentum. Secured on the shaft 24, is a five pointed star wheel 33, as shown in large detail in Fig. 8, and mounted upon the frame 95 bar 23, is a spring pressed arm 34, provided with a roller 35, at its lower end which at all times engages the star wheel 33, as shown in Figs. 6 and 8, and which serves as a brake therefor, and owing to the deep indentations 100 between the teeth of said star wheel 33, serves to instantly lock the same from further movement after it has been thrown characteristically by the mutilated gear.

105 Slightly at the rear of the nickel registering mechanism is the penny recorder, said coin being the next smaller size of coin after the nickel. As shown, said penny recording mechanism is supported upon a frame bar 36, corresponding with the frame bar 23, and beneath which and adjacent the frame plate is journalized a shaft substantially identical in all particulars with that before described with reference to the nickel counting shaft and on the outer end of which is a 110 star wheel 37, in advance of which is the guide plate 96, similar to the guide plate 32, before described, but which permits pennies and dimes to pass beneath the same.

115 The mutilated gear 39, on the penny shaft 120 is provided with but a single tooth (see Fig. 4) inasmuch as the star wheel is provided with five teeth as before described, in consequence, necessitating an entire revolution of the shaft to count five cents upon the 125 veeder, or, in other words, to actuate the master gears to register one count upon the veeder. Said shaft is short and the star wheel 37, is arranged closely to the periphery of the carrying wheel and is designed to 130

intercept only the pennies presented thereto by the carrying wheel and to permit dimes to pass without registering thereon. In a like manner to that before described, a brake such as shown in Fig. 8, is provided to hold said shaft from throw or incorrect movement because of the momentum of the mechanism. Next adjacent the penny registering mechanism and at the rear thereof is the 10 mechanism for registering dimes. This is identical in all respects with the counting mechanisms just described and is likewise provided with its five pointed star wheel 40, on the outer end of the shaft 41, therefor, as 15 shown in Fig. 7. Said shaft is provided with a star brake wheel 42, and detent lever 44, such as before described and illustrated in Fig. 8. A bevel pinion 45, at the inner end of said shaft meshes with a corresponding bevel pinion 46, on a shaft 46^a, on the upper end of which is rigidly secured the mutilated gear 47, in this instance also provided with five teeth spaced equal distances apart. Said mutilated gear 47, meshes with 25 the pinion 48, on the shaft 48^a, and rigidly secured on said shaft is a larger pinion 49, which meshes with the master gear 12. The relative size of the pinions 49 and 48 are as two to one so that although the shaft is rotated by one-fifth of a revolution by a dime passing beneath the guide 21, and engaging the star wheel 37, nevertheless, owing to the arrangement of the two to one gears as before described each dime causes a rotation 30 of the master gear twice as great as occasioned by each nickel in registering, and in consequence, records two fares upon the accumulating veeder.

The mechanism before described is rigidly 40 mounted upon a base plate 50, as shown in Fig. 2, upon which is also supported and rigidly secured the inclosing casing 51, of cast metal or other suitable material and in the bottom of the case so formed is provided 45 a drawer 52, provided with a plurality of compartments for nickels, pennies and dimes respectively, and as shown, near the front end of each of said compartments the base plate is cut away to afford an aperture 98, therethrough to admit the counted coins into 50 the respective compartments. As shown also, a fare box or receptacle is mounted on and rigidly secured to the top of the casing 51, and is adapted to receive the fares when deposited therein by the conductor or passenger. Said fare box, as shown, is substantially 55 rectangular and nearly cubical and embraces posts 54, at each corner thereof rigidly engaged on the casing and secured between the posts are plates of glass, mica, celluloid or other suitable material indicated by 55.

Connected in the top of the fare box is a 60 hopper 56, open at its lower end and communicating immediately with a tortuous

channel or passage through which the coin is discharged into the bottom of the box. As shown, in Figs. 15, 16, and 17, said channel or passage is formed by means of a plurality of metallic or other suitable side plates 56, 57, 58, 59, 60, and 61, affording opposite sides of the passage and the remaining side walls of which are afforded by suitably shaped or cut strips of mica, celluloid or glass or other transparent material. 75 As shown, the inclined side plate 60, projects beyond the side plate 61, and is provided with serrations or teeth and in a like manner the engaged faces of the plate 58, and the hinged door 62 at the bottom of 80 said passage are provided with complementary teeth, as shown in Fig. 16, which intermesh, thus precluding the unauthorized removal of coin from the machine through said passage, as, for instance, by 85 the insertion of a cord bearing adhesive material and adapted to engage a coin in the bottom of the box.

At the bottom of the fare box is provided an inclined floor 63, which, near its bottom, 90 is provided with a downwardly opening door 64, adapted to drop the coin there-through as hereinafter more fully described. Secured around the carrying wheel at the sides and bottoms of the frame plate is an 95 upwardly extending wall 66, affording a hopper into which the coin are delivered from the fare box by gravity. As shown, supported on the wall of said hopper and the face of the carrying plate are chutes 100 corresponding in number with the number of dimensions of coin to be handled by the machine, and in this instance, indicated respectively by 67, 68, and 69, and appropriated in the order named for nickels, 105 pennies and dimes. Said chutes comprise bottom and top plates. As shown, the bottom and top plates 70 and 71 respectively of said chutes are each constructed of a single plate of metal of which the top plate 71, 110 is materially longer than the bottom plate. Said chutes are arranged as shown in Figs. 1 and 2, to overlie the carrying wheel with the mouths of said chutes directed downwardly, as shown in Fig. 2, to the respective 115 compartments in the drawer. As shown also, a shaft 99, is journaled beneath the fare box and a trap door 64, is secured thereto as shown in Fig. 14. An inclined floor 72, is secured beneath the fare box into which 120 the trap door opens, and said wall extends to the wall of the casing, as shown in Fig. 2, and is intended to serve as a receptacle for articles dropped into the box that the machine may be not capable of counting. 125

Means are provided for automatically discharging the fare box at regular intervals. For this purpose, as shown, a bell crank lever is fulcrumed on the frame plate 2, with one arm 74, thereof extending beneath and 130

normally supporting a door 75, positioned to discharge the coin therefrom direct to the hopper 66. The opposite arm 76, of said bell crank extends downwardly into close relation with the shaft 10, into position to be struck by a tappet arm 77, secured on said shaft, and as shown, a spring 78, is secured on said arm and the frame plate and acts normally to hold said arm 76, downwardly in position to support the door and the coin thereon.

The door 75, as shown in Fig. 14, is constructed in two sections each pivoted to a hinge rod 88, adapting the corresponding ends of the sections to drop downwardly. An arm 89, is secured to one section and returns the other section to normal therewith after each opening. Should refuse matter or material other than coin be inserted in the box, it is readily dumped by the mechanism illustrated in Figs. 2, 5, and 14. For this purpose, as shown, a spring pressed latch 79, is slidably engaged through the top of the casing alongside the fare box and is provided with a spring 80, secured thereon which normally holds said plunger or latch in an elevated position. A member through which said plunger 79, extends, has one arm 81, directed laterally therefrom into position to engage the outer end or extremity of the arm 74, of the bell crank before described. On the opposite side of the plunger the member is provided with an arm 86, which extends downwardly and is obliquely directed at the bottom to provide a cam face which engages a cam 100, formed by flattening the end of shaft 99, for the trap door 64, and a strong spring 82, holds said cam 100, against the bottom of the arm 81, thereby normally closing the trap door. It will be noted that the arm 86, bears against cam 100, and that arm 81, is spaced a distance above bar 74. Owing to this construction the door 64, starts to close aperture 101, before door 75, starts to open thereby allowing the refuse matter to drop onto plate 72.

The operation is as follows: Coins are dropped into the fare box and the rotation of the driving shaft 10, serves to intermittently open door 75, to drop said coin to the hopper 66, to be taken up by the carrying wheel selectively and delivered to the counting means. Inasmuch as the carrying wheel is capable, (owing to the construction of the recesses in the periphery thereof) to carry any of several sizes of coin securely held therein, it follows that either pennies, dimes or nickels are indiscriminately selected by and received into the pockets in the carrying wheel and thence moved upwardly to counting position. The periphery of the carrying wheel is made as thin as the thinnest coin to be carried thereby. To obviate the possibility of an additional coin finding its way into a pocket, a spring con-

trolled pivoted stripper arm 84, is suitably engaged in a recess and is so positioned to engage any excess coin in any pocket in the periphery and strike the same back into the hopper but the same is so positioned as to permit any coin singly carried in a pocket to pass beneath the same. Having passed the stripper plate, the coin, if less than a nickel, will pass beneath the guide 32, and will not be engaged by any of the teeth of the star wheel for said mechanism.

Should, however, a nickel be presented, the periphery thereof is brought positively against one of the teeth in the star wheel 25, rotating the same against the resistance of the spring detent 34, the roller 35, of which is engaged at all times between the teeth of the star brake wheel 33. In consequence, when the counting mechanism has been actuated sufficiently by the pressing of the nickel against the teeth of said star wheel, then the friction roller 35, has passed the point of the star brake wheel 33, and is entering the incline on the opposite side thereof. In consequence, the spring on said detent snaps the roller somewhat violently to normal, completing the movement of the star wheel and causing the next succeeding tooth of the star wheel to snap the coin out of the seat in the carrying wheel from whence it slides down the appropriate chute to its receptacle or drawer. In a similar manner the other mechanisms operate, that for pennies permitting the five pennies to pass before registering. In each event, however, the coin is snapped from the pocket and delivered into the appropriate chute where it falls by gravity to its compartment. Owing to the two to one arrangement of gears for the dime wheel, each dime registers two fares. All of said pinions are meshed directly with and deliver an impulse to the master gear sufficient to actuate the same characteristically to register. The pinion driving the accumulator shaft is also at all times meshing with the master gear and also has geared relation with the veeder or counter. In consequence, each partial revolution of the master gear produces characteristic movement in the veeder correctly counting the coin delivered to the box.

As shown in Figs. 12 and 13, the ball bearing is slightly modified and comprises a sleeve 105, secured on the hub 5, which is provided with a cone bearing face 106. A cone member 107, is threaded on the outer end of the sleeve and the balls are secured between said cones and rings 108, integral with a cylinder 109, to which is integrally secured the master gear 110.

Of course, we are aware that numerous details of this construction may be varied, and we have attempted to show but one practical illustration of our invention and that the commercial form in which the same

is going extensively into use. We therefore do not purpose limiting ourselves otherwise than necessitated by the prior art, but purpose claiming broadly a counting and separating mechanism for coin in which the coins may be dumped indiscriminately and are selectively removed and sorted and delivered, each to a special place of deposit.

We claim as our invention:

- 5 1. In a fare register a fare box to receive the coin indiscriminately mixed, a rotative carrier adapted to engage and move the coins one by one to discharge position, a gear wheel journaled co-axially with said carrying wheel, mechanisms arranged about the periphery of the carrying wheel embracing parts projecting into the path of the coin carried in said wheel and adapted to be actuated thereby, mutilated gears driven by said parts, pinions driven by said mutilated gears and meshing with the first named gear, a registering mechanism and a gear for driving the same meshing with said first named gear.
- 10 2. In a fare register a fare box to receive the coin indiscriminately mixed, a rotative carrier adapted to engage and move the coins one by one to discharge position, a gear wheel journaled co-axially with said carrying wheel, mechanisms arranged about the periphery of the carrying wheel embracing parts projecting into the path of the coin carried in said wheel and adapted to be actuated thereby, mutilated gears driven by said parts, pinions driven by said mutilated gears and meshing with the first named gear, a registering mechanism, a gear for driving the same meshing with said first named gear, and mechanically operated means for dumping the coin from the fare box to the carrying wheel by rotation of the carrying wheel.
- 15 3. A fare counter and register embracing a receptacle to receive coin indiscriminately mixed, a rotative shaft, a rotative carrier secured thereon and having pockets in its periphery each adapted to hold but a single coin of any of the denominations received in the receptacle, a master gear journaled on said shaft, a registering mechanism driven thereby a toothed wheel journaled at the rear of the carrying wheel and at an angle with the plane thereof and projecting into close relation with its periphery and adapted to be rotated by engagement with the coin therewith, a mutilated gear driven from said toothed wheel, a pinion intermittently driven thereby and meshing with the master gear and yielding detents acting to limit the rotation of the master gear with each impulse of said pinion.
- 20 4. In a fare register the combination with a rotative carrying mechanism adapted to engage the coin selectively from an indiscriminate mass, of a master gear journaled

to rotate independently of the conveying mechanism, independent actuating means therefor geared thereto, one for each denomination of coin to be counted and each affording a part projecting into the path of the coin moved by the carrying mechanism, and a registering mechanism also geared to said master gear.

5. In a fare register a rotative carrying wheel adapted to selectively engage and move indiscriminately mixed coin from a mass one by one, a single register, mechanisms for separating the coins into their denominations and actuating the register by one of said mechanisms for each coin each mechanism appropriated to a particular denomination of coin and embracing a rotative element projecting into the path of the moving coin, a single master gear driven thereby and connected to drive said register, and a tripping device actuated simultaneously with the actuation of the register and acting to discharge the coin registered to a place of deposit for that denomination.

6. In a fare register the combination with a carrying and separating wheel and its shaft for rotating the same, of a master gear journaled on said shaft, a registering mechanism driven by said gear and mechanisms adapted to be actuated only by, and appropriated each to but one denomination of coin and operatively connected with said gear, each to rotate the same thereby actuating the register to an extent characteristic only for that particular denomination, and an ejecting device for discharging the coin from the wheel as registered.

7. In a fare register a shaft, a coin carrying wheel rotatable therewith, a gear journaled on the shaft, mechanisms appropriated to different coin denominations and actuated by the respective coins carried by said wheel, gears meshing with the aforesaid gear and actuated by the respective mechanism and a register operated from the first named gear.

8. In a fare register a shaft, a coin carrying wheel rotatable therewith, a gear journaled on the shaft, mechanisms appropriated to different coin denominations and actuated by the respective coins carried by said wheel, gears meshing with the aforesaid gear and actuated by the respective mechanism, a register operated from the first named gear, a fare box, a door closing the same, and mechanism operated with the rotation of the carrying wheel for intermittently opening the door to discharge the coin to the carrying wheel.

9. In a fare register for coins of various denominations a shaft, a carrying wheel rotatable therewith, a master gear on the shaft rotatable independently thereof, mechanism operated by coin carried by the carrying wheel for rotating the master gear in proportion to their respective coin values,

and an accumulating registering mechanism operated by rotation of the master gear.

10. In a fare register a shaft, a carrying wheel rotatable therewith, a master gear on the shaft rotatable independently thereof, mechanisms operated by coin carried by the carrying wheel for rotating the master gear, a registering mechanism operated by rotation of the master gear, a brake for each of 10 said mechanisms, and a brake for the master gear.

11. In a fare register a shaft, a carrying wheel rotatable therewith, a master gear on the shaft rotatable independently thereof, 15 mechanisms operated by coin carried by the carrying wheel for rotating the master gear, a registering mechanism operated by rotation of the master gear, independent coin chutes for receiving the different denominations of coin, and means discharging each 20 coin as registered from the carrying wheel to its appropriate coin chute.

12. In a fare register a shaft, a carrying wheel rotatable therewith, a master gear on the shaft rotatable independently thereof, mechanisms operated by coin carried by the carrying wheel for rotating the master gear, an accumulating registering mechanism operated by rotation of the master gear, independent 30 coin chutes for receiving the different denominations of coin and means actuated by the passing coin for discharging the coin from the carrying wheel to its appropriate chute, a hopper extending partly around the carrying wheel, a fare box having an opening to deliver to the hopper, a door for closing the opening and mechanism for automatically opening the door when the carrying wheel is rotated.

13. In a fare register a shaft, a carrying wheel rotatable therewith, a master gear on the shaft rotatable independently thereof, mechanisms operated by coin carried by the carrying wheel for rotating the master gear, a registering mechanism operated by rotation of the master gear, independent coin chutes for receiving the different denominations of coin and means discharging each 40 coin from the carrying wheel embracing a part of the mechanism which the coin actuates, a hopper extending partly around the carrying wheel, a fare box having an opening to deliver to the hopper, a door for closing the opening, mechanism for automatically opening the door when the carrying wheel is rotated, a receptacle for receiving refuse material, a door normally closed and adapted when closed to afford communication between the fare box and hopper and 50 when open to afford communication between the refuse receptacle and fare box, and mechanism for simultaneously actuating both doors to deliver into the receptacle only.

14. A fare register comprising carrying

and separating elements for the coin, a master gear, mechanisms, each adapted to be operated by the coin of one denomination only while actuated by the carrying element, a gear operated by each and meshing with the master gear, a pinion meshing with the master gear and driven by rotation thereof and a registering mechanism operated by said pinion.

15. A fare register comprising carrying 75 and separating elements for the coin, a master gear, mechanisms, each adapted to be operated by the coin of one denomination, only while actuated by the carrying element, a mutilated gear operated by each of 80 said mechanisms and meshing with the master gear, a pinion meshing with the master gear and driven thereby, a registering mechanism operated by said pinion, a brake for the master gear, and a brake for 85 each coin actuated mechanism.

16. A fare register comprising a separating and carrying element for the coin, a master gear, mechanisms, each adapted to be operated by the coin of one denomination carried by said element, a gear operated by each mechanism and meshing with the master gear, a pinion meshing with the master gear and driven by rotation thereof, a registering mechanism operated by said 95 pinion, a brake for the master gear, a brake for each coin actuated mechanism, a chute for each coin denomination, a drawer having an independent compartment for each chute and means ejecting the coins from the 100 carrying element to the respective chutes.

17. In a fare register an actuating shaft, a worm thereon, a driven shaft, a worm gear thereon meshing with the worm, a coin carrying wheel secured on the shaft, a ball 105 bearing on said driven shaft, a master gear secured thereto, actuating mechanisms operated by the coin carried by said wheel adapted to rotate the master gear proportionately to their fare values, and a registering mechanism operated from the master gear.

18. In a fare register an actuating shaft, a worm thereon, a driven shaft, a worm gear thereon meshing with the worm, a coin carrying wheel secured on the shaft, a ball bearing on said driven shaft, a master gear secured thereto, actuating mechanisms operated by the coin carried by said wheel and adapted to rotate the master gear proportionately to the fare value of the coin, a registering mechanism operated from the master gear, gravity discharge chutes for the coin and a drawer for receiving the coin 115 from the chutes.

19. In a fare register an actuating shaft, a worm thereon, a driven shaft, a worm gear thereon meshing with the worm, a coin carrying wheel secured on the shaft, a ball bearing on said driven shaft, a master gear 120

secured thereto, actuating mechanisms operated by the coin carried by said wheel adapted to rotate the master gear, a registering mechanism operated from the master gear, gravity discharge chutes for the coin, a drawer for receiving the coin from the chutes, a hopper for holding the coin for the carrying wheel to receive the same, and a receptacle for refuse not to be counted.

10 20. In a fare register, a registering mechanism, a master gear, a ratchet gear rigidly connected thereto, a pawl to prevent reversal thereof, mechanism operated by said master gear for actuating the registering mechanism and a plurality of coin operated mechanisms all having a geared connection with the master gear.

20 21. In a fare register, a registering mechanism, a master gear, mechanism operated thereby for actuating the registering mechanism, a plurality of coin operated mechanisms all having a geared connection with the master gear, and each adapted to rotate the master gear a distance dependent upon the amount to be registered and an inclined rotatable disk for moving the coins to selectively operate the mechanisms.

25 22. In a device of the class described an inclined face plate, a coin carrying disk rotatably mounted in a recess therein, means projecting through said plate and adapted to be contacted and actuated by coins of a certain denomination carried by said disk, a plurality of mechanisms, one for each of said means, mounted on the rear surface of said plate to be driven thereby, a shaft, means transferring the movement of each of said mechanisms to said shaft, said projecting means so spaced upon said plate relative said movable disk as to preclude simultaneous operation thereof by the respective coins carried on the disk, a register adapted to be driven by said shaft to total the count of the coins, a worm gear connected to said movable disk, a worm shaft for driving the same, and means associated with said shaft to intermittently admit a charge of coins upon said movable disk.

30 23. In a device of the class described a supporting plate, a coin carrying disk mounted to rotate in a recess therein, coin engaging means projecting through apertures in said plate, each one thereof adapted to engage coins of certain denomination carried by said disk, a register, a shaft connected to drive the same, a master gear freely journaled coaxially with said disk, mechanisms in train with said master gear and adapted to be actuated by said coin engaging means, and a worm and gear adapted to rotate said coin carrying disk.

35 24. A coin separating and counting mechanism embracing a hopper to receive a mass of indiscriminately mixed coins, a carrying element to convey said coins one by one from

said mass of indiscriminately mixed coins, a worm gear connected thereto, a worm shaft for driving the same, register actuating mechanisms arranged around said carrying mechanism in position to be selectively actuated by the respective coins in accordance with their denomination, and adapted to eject the coins from the carrying element simultaneously with their actuation by said coins, means mounted coaxial with said worm gear adapted to be driven by said actuating mechanisms, and a register operatively connected to be actuated independently and characteristically by each of said register actuating mechanisms through said means.

40 25. In a machine of the class described separating and counting mechanisms embracing a hopper adapted to receive coins indiscriminately mixed, a plurality of counting mechanisms, one for each denomination of coin, a rotatable carrying mechanism adapted to engage and carry coins one by one from the mass into operative relation with the respective counting mechanisms, a worm gear connected to said carrying mechanism, a worm shaft for driving the same, means mounted coaxial with said worm gear to receive the drive from said counting mechanisms, a register adapted to be actuated by each of said counting mechanisms through said means, and mechanism associated with each register actuating mechanism for discharging the coin from the carrying mechanism after the count is registered.

45 26. A coin separating and counting mechanism embracing a hopper, a rotative carrying element having the periphery thereof projecting thereinto and adapted to carry the previous mixed coin therefrom one by one, a worm gear connected to said carrying element, a worm shaft for driving the same, actuating mechanisms arranged peripherally around the carrying element, a register, an actuating shaft therefor, and a gear mounted coaxial with said carrying element actuated by each of said actuating mechanisms, means transferring the movement thereof to said actuating shaft sufficiently to afford the characteristic count on the register for every denomination of coin.

50 27. The combination with a carrying element of a worm drive therefor, a plurality of shafts disposed radially with respect to said carrying element, a counting star wheel on the end of each shaft in position to be engaged by a coin of suitable diameter as the same passes the wheel, a mutilated gear adapted to be driven by each of said shafts, one gear for each shaft, a master gear driven therefrom, and a single register actuated from said master gear adapted to record the count for each coin selectively and independently.

28. In a machine of the class described a carrying element for carrying a plurality of indiscriminately mixed coins, a worm gear connected thereto, a worm shaft for driving the same, a plurality of contact elements, each adapted to be actuated by a coin of certain denomination as the carrying element moves the coins therepast, a totalizing gear therefor coaxial with said worm gear, a register, and operative connections between the respective actuating elements and the register, whereby each actuates the register to register its count independently of the other elements.
- 15 29. In a machine of the class described mechanisms appropriated to different money denominations, one gear mounted to receive the drive from all thereof, a register actuated thereby, a carrying element adapted to gather and advance a plurality of coins from an indiscriminately mixed mass adapting the coins while on said carrying element to selectively actuate the proper mechanisms, and a

worm and gear connection for driving said carrying element.

30. In a machine of the class described mechanisms appropriated to different money denominations, a register actuated thereby, a carrying element adapted to gather and advance a plurality of coins from an indiscriminately mixed mass adapting the coins while on said carrying element to selectively actuate the proper mechanisms, a master gear adapted to be driven by each of said respective actuating mechanisms independently and acting to transfer the count to the total register, and worm and gear driving connections for operating the machine.

In testimony whereof we have hereunto subscribed our names in the presence of two 40 subscribing witnesses.
